UNITED STATES PATENT OFFICE.

WILLIAM MILTON BROWN, OF JOHNSTOWN, PENNSYLVANIA, ASSIGNOR
TO THE LORAIN STEEL COMPANY, A CORPORATION OF PENNSYLVANIA.

ELECTRIC-RAILWAY SYSTEM.

No. 830,131.

Specification of Letters Patent.

Patented Sept. 4, 1906.

Application filed April 27, 1905. Serial No. 257,764.

To all whom it may concern:

Be it known that I, WILLIAM MILTON BROWN, of Johnstown, in the county of Cambria and State of Pennsylvania, have invented 5 a new and useful Improvement in Electric-Railway Systems, of which the following is a full, clear, and exact description, reference being had to the accompanying drawings, which form a part of this specification.

10 My invention has relation to third-rail electric-railway systems of that class wherein the third rail is in sections insulated from each other, the sections being successively engaged by a passing car or train through 15 the medium of electromagnetic switches, which are closed by a magnet or magnets on the car or train.

My invention is designed to provide a system of this character in which the third rail, 20 together with one of the track-rails, may be used to transmit magnetism from the car-magnet to the armatures of the circuit-closing switches, thereby obviating the use of an independent rail or rails for this purpose and 25 also permitting the use of a comparatively small and light car-magnet.

A further object is to so arrange the circuit-closing devices that they may be readily accessible for inspection and repairs and also 30 protected against the entrance of water.

With these objects in view my invention consists in the novel construction, arrangement, and combination of parts, all substantially as hereinafter described, and pointed 35 out in the appended claims, reference being had to the accompanying drawings, in which—

Figure 1 is a plan view of a section of railway embodying my invention; Fig. 2, a side 40 view of a portion of track and car thereon and illustrating the car-magnet and current-collecting device; Fig. 3, a transverse section of the track and showing in end elevation a portion of a car thereon; Fig. 4, a top 45 plan view of one of the circuit-closing devices and showing its connection to the adjacent rails, and Fig. 5 a section on the line 5 5 of Fig. 4.

The numerals 1 and 2 designate the usual 50 track-rails, and 3 the sectional third rail, which in the present instance is shown supported outside of the rail 2 on insulators 4.

Between the rails 2 and 3 are placed the circuit-closing switches, which are indicated

in Fig. 1 by the numeral 5, which designates 55 more particularly the insulating cover portions thereof. These switch devices, as herein shown, with the exception of the cover and the means by which they are connected to the rails 2 and 3, are of the general character 60 described and claimed in the patent to McFeaters, No. 618,179, dated January 24, 1899, with certain improvements thereto. They each consist of an insulating body or base 6, having a cavity in which is seated in 65 fluid or semifluid insulating material 7 a sectional cup 8, of insulating material. In this cup is an armature 9, carrying an electrode 9^a, arranged to be lifted by the car-magnet into contact with a fixed electrode 70 10. The electrode 9^a is connected by a flexible conductor 11 with a conducting-piece 10^a in the bottom of the cup and which is in turn electrically connected with a supply-cable 12. The cable 12 is led into the terminal plug 13 through the sleeves 14 and 15. 75

The electrode 10 is fastened to and electrically connected with conducting-piece 16 in the top of the cup. The top portion or cover 5 is convex on its upper surface, and its 80 lower surface is shaped to receive the top portion of the cup 8. Said cover is of insulating material and is provided with the grooves 5 on its upper surface for the purpose of carrying off water from its surface. 85 This cover entirely closes in the cavity in which the switching mechanism is located and keeps all water therefrom. Molded in this cover is a conductor 17 and also two arms 18 and 19, of magnetic material, the 90 arm 18, to which the conductor 17 is electrically connected, being also of good conducting material. The conductor 17 has a screw-threaded aperture in its under side, which receives a threaded stud 16^a of the conductor 95 16, whereby the cup and cover are securely joined. The arm 18 is shaped to form a separable joint at 20 with an arm 21, which is connected to the web of the third rail 3 and which is of good magnetic and electric 100 conductivity. The arm 19 forms a similar separable joint at 22 with an arm 23, secured to the web of the track-rail 2, and which is a good magnetic conductor.

24 designates the car-magnet, having an 105 energizing-coil 25 and two parallel depending pole-pieces 26 and 27, the magnet being so mounted on the car that these pole-pieces

will be, respectively, over the rails 2 and 3, as clearly shown in Fig. 3. The coil 25 may be connected in the car-circuit in any usual manner.

- 5 Carried by the pole-piece 27 by means of the links 28 and a guiding-stud 29 is a current-collecting shoe 30, which makes contact with the surface of the third rail 3, being held to such contact by means of a spring 31.
- 10 The operation will be readily understood. The car-magnet on a passing car being energized in any suitable manner, wherever it comes over one of the switch devices a magnetic circuit is at once formed from one of its 15 poles through the rail 3, the arms 18 and 21, the armature 9, the arms 19 and 23, and rail 2, back to the other pole of the magnet. The armature 9 is thereby lifted, bringing the electrodes 9^a and 10 into contact, and thereby 20 electrically connecting the conductor 16 with the cable 12. The current now passes from the conductor 16 through the conductor 17, arms 18 and 21, to rail 3, and thence to the collecting-shoe 30, and from thence to the 25 car-motors. (Not shown.)

One or more of the switches may be connected to each section of the rail 3. By means of the joints at 20 and 22 the cover 5 may be quickly removed, bringing with it the 30 cup 8, which can then be detached, there being a separable connection at 32 between the conductor 10^a and the terminal plug 13. While I prefer to use circuit-closing devices or switches of the character described, it will 35 be readily understood that any suitable form of switch may be employed.

Having thus described my invention, what I claim as new, and desire to secure by Letters Patent, is—

- 40 1. In an electric-railway system of the character described, the combination of the track-rails, a sectional third rail adjacent to one of said track-rails, and a series of magnetically-actuated circuit-closing devices or 45 switches situated between the third rail and the adjacent track-rail, and lateral arms connected to said third rail and the adjacent track-rail and forming magnetic connections to said switches.
- 50 2. In an electric-railway system of the character described, the combination of the track-rails, a sectional third rail adjacent to one of said track-rails, and a series of magnetically-actuated circuit-closing devices or 55 switches situated between the third rail and the adjacent track-rail, and lateral arms connected to said third rail and the adjacent track-rail and forming magnetic conductors to said switches, one of said arms being also 60 in electrical connection with one of the switch members and with the third rail.
3. In an electric-railway system, of the character described, the track-rails, a sectional third rail adjacent to one of the track-rails, magnetically-actuated circuit-closing 65

devices between the third rail and the adjacent track-rail, arms connected to said third rail and track-rail and extending to the circuit-closing devices to complete magnetic circuits for the armatures thereof, and an electrical connection between a member of each circuit-closing device and a section of the third rail, in combination with car-magnets each having two pole-pieces arranged to travel on the third rail and adjacent track-rail, respectively, and a current-collecting device carried by said magnet and arranged to engage the said third rail. 70

4. In an electric-railway system of the character described, the combination with a third rail and an adjacent track-rail, of magnetically-actuated circuit-closing devices located between the said rails, and arms connected to each of the said rails and leading to the circuit-closing devices to form a magnetic circuit therefor, said arms being each 85 formed in two separable sections. 80

5. In an electric-railway system of the character described, the combination with an inclosed, magnetically-actuated circuit-closing device, of a cover portion of insulating material, and having a convex, grooved, upper surface, and conductors of magnetic material extending into said cover portion in proximity to the circuit-closing device. 90

6. In an electric-railway system of the character described, the combination with a cup of insulating material containing magnetically-actuated circuit-closing devices, of a cover portion of insulating material fitting 100 over the said cup, and having secured therein laterally-extending arms of magnetic material. 95

7. In an electric-railway system of the character described, the combination with a cup of insulating material containing magnetically-actuated circuit-closing devices, of a cover portion of insulating material fitting over the said cup, and having secured thereon laterally-extending arms of magnetic material, one of said arms being also electrically connected with the said circuit-closing devices. 110

8. In an electric-railway system of the character described, the combination with a cup or vessel of insulating material containing magnetically-actuated circuit-closing devices, of a cover portion of insulating material fitting over and detachably secured to the said cup. 115

9. In an electric-railway system of the character described, the combination with a cup or vessel of insulating material containing magnetically-actuated circuit-closing devices, of a cover portion of insulating material fitting over and detachably secured to the said cup, said cover portion also having secured therein laterally-projecting arms of magnetic material. 125

10. In an electric-railway system of the 130

character described, the combination with a base member having a cavity therein, a closed vessel of insulating material seated in the said cavity, and a cover portion of insulating material fitting over the said vessel and closing the said cavity, said cover portion having a convex, grooved, upper surface.

11. In an electric-railway system of the character described, the combination with a base member, having a cavity therein, a closed vessel of insulating material removably seated in the said cavity, a cover portion of insulating material fitting over the said cup and detachably connected thereto, said cover portion having therein an electric conductor connected with circuit-closing devices within the said cup.
12. In an electric-railway system of the

character described, the combination with the track-rails, of a sectional third rail adjacent to one of said track-rails, magnetically-actuated circuit-closing devices between the third rail and the adjacent track-rail, arms of magnetic material extending from the third rail and the adjacent track-rail to the said circuit-closing devices, electrical connections from the said devices to the sections of the third rail and means for electrically insulating said devices from the adjacent track-rail.

In testimony whereof I have affixed my signature in presence of two witnesses.

WILLIAM MILTON BROWN.
